UNITED STATES PATENT OFFICE

2,604,852

PUMP IMPELLER

Millard H. Baker, St. Louis, Mo., assignor to
Fairbanks, Morse & Co., Chicago, Ill., a corpora-
tion of Illinois

Application May 3, 1948, Serial No. 24,787

3 Claims. (Cl. 103—96)

1

This invention relates to peripheral type pumps, and has particular reference to an improved impeller or rotor member for such pumps.

An object of the invention is to provide for peripheral pumps, an impeller formed of a flexible, resilient material such as rubber, which is reinforced for structural stability in pump operation.

Another object is to provide an impeller of the foregoing character, which is more economical of manufacture than the usual or prevailing all-metal impellers, and which will increase pump efficiency by reason of an improved seal effected by the rubber impeller at the partition or block between the pump casing inlet and outlet.

A further object is to provide a structurally reinforced rubber impeller of bucket type for peripheral pumps, wherein the annular bucket section of the impeller is formed entirely of rubber, to afford a yielding resiliency of the buckets and vane elements thereof, which will reduce bucket and pump casing damage by solid objects and abrasive material which may enter and pass through the pump.

Other objects and advantages of the present improvements will appear from the following description of a presently preferred embodiment of the invention as illustrated in the accompanying drawing, wherein:

Fig. 1 is a sectional elevation of a pump structure embodying the presently improved impeller, the section being taken along line 1—1 of Fig. 2;

Fig. 2 is a sectional view in plan, through the pump casing showing the impeller therein, and

Fig. 3 is a fragmentary peripheral plan view of the impeller as taken from line 3—3 in Fig. 2.

Referring to the drawing, the pump assembly shown in Fig. 1 includes a pump housing 10 providing a side wall 11, and an internal wall 12 of annular extent, defining in part a fluid channel 14. A removable casing closure member 15 secured to casing 10 as by suitable bolts 16, serves to complete the channel 14. Casing 10 further is formed to provide an inlet fitting 18 providing a passage 19 communicating with channel 14, and an outlet fitting 20 having a passage 22 communicating with channel 14. The inlet and outlet passages of the fittings are separated by a partition wall or block 23 providing a curved surface 24 for cooperation with the periphery of the rotor 26.

Rotor 26 is mounted upon and suitably secured to one end of a shaft 27, the latter extending through casing wall 11 for connection to suitable driving means such as an electric motor

2

or the like (not shown). In its passage through wall 11, the shaft 27 is sealed against fluid leakage by a suitable packing or sealing gland structure 28.

Referring now to the structure of the impeller 26, the impeller provides a disc body 30 of a flexible, resilient material such as rubber, a shaft mounting hub 31 and a body reinforcing member or disc 32. In the present embodiment, it is preferred to provide the hub 31 and reinforcing disc 32 as an integral or one-piece structure of metal such as brass or bronze. The rubber body 30 is molded about disc 32 to effect a firm assembly. As appears in the drawing, the radial extent of reinforcing disc 32 may be, and by present preference is, determined to be such that the disc periphery terminates appreciably inwardly of the periphery 34 of the impeller body, preferably terminating near the root circle of the impeller buckets 35. In molding the rubber body 30 to disc 32, the molding operation includes formation of the peripheral section of the rubber body to afford a central annular web 36 tapering convergently toward the periphery of the rotor, and a series of equally spaced ribs 38 on each side of the center web 36. The web and ribs form the rotor buckets 35. Preferably and as illustrated in Fig. 3, the ribs 38 are relatively staggered on the opposite sides of the web 36 to effect the illustrated staggered relation of the buckets.

Adjacent hub 31 the impeller is provided with openings 39 through the rubber body and reinforcing disc 32, these openings providing fluid communication from one side to the other of the impeller in the casing chamber 40, whereby to afford equalization of fluid pressures on the opposite sides of the impeller. Moreover, in order to afford greater flexibility of the impeller 26 inwardly of the bucket zone thereof, the opposite faces 42 of the body may be recessed as shown, to provide alternate ribs 43 and channels 44. In the present example, such formation of the impeller faces 42 may be effected so as to provide the channels 44 on each side, as a single spiral channel directed with respect to the direction of impeller rotation, such as to utilize centrifugal force to carry fluid along the channels toward the bucket zone of the impeller. This will tend to reduce to a material degree, the extent of fluid leakage from the impeller channel 14 to the central casing chamber 40.

It will appear now that an improved seal is here effected between the periphery of the rubber impeller and the surface 24 of the casing

55

partition 23, as well as between the lateral surfaces 46 of partition 23 and the bucket-forming ribs 38. The seal thus obtaining at the partition, serves to reduce fluid leakage-loss between the pump outlet and inlet, thereby improving 5 pump efficiency.

It is to be emphasized here that one of the important features of the present improvements lies in the resiliency of the bucket section of the impeller, this portion of the impeller being entirely of rubber since the reinforcing disc 32 terminates short thereof, as illustrated. Consequently, it will be appreciated that the buckets may yield in the presence of solid objects which may enter the pump, and may allow such objects 10 to pass to discharge without such damage to the buckets as would otherwise occur were the impeller structure formed of metal. Moreover, in the event of the entrance of solid objects too large for the impeller to carry to discharge without some damage to the pump, it will appear 15 that the bucket ribs being of rubber, may absorb the damage as by shearing, to relieve jamming and scoring engagement of the solid object or objects with the sides of the impeller channel 14. Since the present impeller may be manufactured quite economically in comparison to the cost of manufacture of all-metal impellers, the replacement cost in the event of impeller damage, will be much less.

It is to be observed further that in forming the presently improved rubber impeller, the impeller surface configuration and buckets are the result of a single molding operation. Thus is eliminated the expensive machining operations which are required to be performed on metal impellers to effect the peripheral buckets and a running fit of the impeller in the pump.

Having now described a presently preferred embodiment of the invention, as illustrated in 40 the drawing, what is desired to be secured by Letters Patent is:

1. A rotor for peripheral type pumps, comprising a unitary member providing a hub and a radially outstanding disc thereon, a body of rubber encompassing said disc and bonded thereto, said body having its peripheral portion extended outwardly beyond the peripheral margin of the disc and formed to provide a double series of buckets, and said body further providing spiral, fluid-receiving grooves in the opposite faces thereof radially inward of said buckets, the spiral groove in each face of the body being directed with respect to the direction of rotation of the rotor such that fluid received in the groove will be displaced therealong under the influence of centrifugal force, toward the peripheral bucket zone of the rotor body.

2. In a peripheral type pump including a casing providing a fluid channel, relatively adjacent fluid inlet and outlet passages for said channel, and a wall element separating said passages

and providing a channel portion forming a continuation of said casing channel, the combination therewith of a rotor comprising a hub having a disc element radially outstanding thereon, and a body of resilient material embracing said disc and secured thereto, the peripheral portion of said body projecting radially beyond the periphery of said disc and formed to provide an annular series of rotor buckets, said rotor buckets operating in the casing channel and having a running seal in the channel portion of the passage separating wall element, and said body further presenting opposite faces each having a fluid-receiving groove therein of spiral trend terminating adjacent the rotor buckets, the spiral groove in each face being directed in respect to the direction of rotation of the rotor in the pump, such that fluid received in the groove will be displaced therealong under the influence of centrifugal force, toward the terminal of the groove adjacent the rotor buckets.

3. In a peripheral type pump including a casing providing a fluid channel, relatively adjacent fluid inlet and outlet passages for said channel, and a wall element separating said passages and providing a channel portion forming a continuation of said casing channel, the combination therewith of a rotor comprising a hub, a single disc element radially outstanding on the hub, a body of rubber embracing said disc element and bonded thereto, the peripheral portion of said body extending outwardly of the periphery of the disc element and formed to provide an annular series of rotor buckets, and said body presenting opposite planar faces and being formed further, to provide a groove of spiral trend in each face terminating adjacent the rotor buckets, said rotor buckets operating in the casing channel and having a running seal in the channel portion of the passage separating wall element.
